C. F. STOKES ET AL

SAFETY RAZOR BLADE OILER

Filed Nov. 22, 1923

Patented Sept. 8, 1925.

1,552,583

UNITED STATES PATENT OFFICE.

CHARLES F. STOKES AND JOHN F. STOKES, OF NEW YORK, N. Y.

SAFETY-RAZOR-BLADE OILER.

Application filed November 22, 1923. Serial No. 676,226.

To all whom it may concern:

Be it known that we, CHARLES F. STOKES and JOHN F. STOKES, citizens of the United States, and residents of New York, county 5 and State of New York, have invented certain new and useful Improvements in Safety-Razor-Blade Oilers, of which the following is a specification.

Our invention relates more particularly 10 to a device for oiling the edge or edges of a safety razor blade, after it has been used, so as to prevent the edges from rusting, before the next time of use. It is well known that if moisture is permitted to remain on 15 the fine cutting edge of a razor blade, fine particles of rust will be formed and the next time the blade is used, it will be found that it is dull. With the ordinary safety razor, such as the Gillette, it is, therefore, customary and advisable, after shaving, to clean 20 the razor and thoroughly dry the blade before putting it away. This operation is troublesome and is often neglected, with the result that the blades seldom remain sharp 25 for more than for two or three shaves.

If, however, the razor, without being disassembled, is cleaned and dried with reasonable care and the edges of the blade oiled, 30 in any suitable manner as by contact with oil pads or other suitable material, impregnated with oil, the razor may be repeatedly used and permitted to remain assembled for an indefinite period, without the edges becoming dulled by rust.

The object of our improved device, therefore, is to provide a simple arrangement of oil pads, against which the edges of the razor blade may rest when the razor is stored until 35 it is to be used again.

When storing the razor after use, it is preferable to store it with the parts assembled and clamped by the handle or the blade assembled with the guard and clamping plate, and a further object of our improvement is to provide means engaging the guard 45 for holding the edges of the razor blade in contact or engagement with suitably disposed oil pads.

Many users of safety razors in their hurry, 50 are inclined to neglect to separate the parts and thoroughly dry the blade and do not trouble to store the parts in the razor case, but leave the razor assembled and place it in the bath cabinet or let it lie around on a 55 table or shelf. Therefore, a further object of our improved blade oiling device is to

provide a holder or support, which may be attached to the wall or other suitable fixture and the razor suspended therein with the edges of the blade in engagement with the oiling pads for oiling and protecting the blade until the razor is used again. 60

With these and other objects in view, we have shown examples of our improved safety razor blade oiling device in the accompanying drawings, in which Fig. 1 shows a side view of our device with the safety razor partially inserted or removed therefrom; Fig. 2 shows the bracket supporting oiler, with the safety razor suspended therein; Fig. 3 is a top plan view of the bracket oiling device; Fig. 4 is a transverse section on the line 4—4 of Fig. 3; Fig. 5 is a longitudinal section through the device with the razor inserted, the section being taken on the line 5—5 of Fig. 2; Fig. 6 represents a longitudinal section through one of the oil pads, on the line 6—6 of Fig. 4; Fig. 7 is a transverse section and Fig. 8 a plan view of a modification of the oiling device. 65 70 75 80

Referring to the drawings, it will be seen that our improved razor blade oiling device, in which the assembled razor may be supported and stored, comprises a suitable bracket member 1, which may be preferably stamped and folded from sheet metal. The bracket 1 is preferably provided with a recess or longitudinal groove at 2 formed by an inward fold of the metal, as will be seen in Figs. 1 and 4 of the drawings. The upper wall 3 of this groove preferably extends upward and outward at an angle and the metal is turned back upon itself at 4 to form a tubular channel for the hinge pin 5. The metal sheet from the end of the fold 4 is 90 then bent upward to form the flange 6, which may be provided with suitable holes for screws 7 or the like, for securing the bracket to the wall or other suitable support, such as the bathroom wall, window casing, or the wall or door of the ordinary bathroom cabinet. The lower wall 8 of the groove or recess 2 in the bracket preferably extends substantially at right angles to the supporting flange 6 and is adapted to engage the under edge of the razor blade guard A for supporting the razor, as shown in Fig. 2 of the drawings. The outer edge of the ledge, formed by the lower wall 8, is joined by a downwardly and outwardly extending guide surface 9, the metal from the lower end of which is bent backward and 100 105

110

downward to form the bracket flange 10, which may be provided with holes, through which similar screws 7 may be passed for securing the bracket to the wall or support.

5 A hinged casing or frame member 11, provided with rolled over tubular hinge portions at 12, is pivotally mounted upon the hinge pin 5, so as to form a hinged member 10 cooperating with and supported by the bracket 1. The free end of the hinged member 11 is preferably bent angularly downward at 13 and provided with a further downward bend at 14 to provide a recess or 15 groove which is completed by a return bend in the form of an inwardly extending flange 15, which, when in normal position, as indicated in Fig. 2 of the drawings, is substantially in a plane with the ledge 8 and is 20 adapted to engage the other edge of the razor blade guard A, and thereby suspend the razor from the bracket.

It will be seen that the bracket 1 and hinged member 11, as thus far described, 25 form a support for holding the safety razor and could readily be used for that purpose alone, but, as previously stated, the object of our improvement is to provide means for oiling the cutting edges of the razor blade to 30 prevent rusting and dulling thereof, after the razor has been used. In order that this may be automatically effected, when the razor is placed in the bracket and hinged member, previously described, suitable oil 35 pads are inserted and carried by the respective members of the device. The bracket member 1 is, therefore, preferably provided with a suitable pad 16 of felt or other absorbent material, which is adapted to be impregnated with any suitable oil or rust-preventing substance. Similarly, the outer edge 40 of the hinged member 11 is provided with a pad 17 of absorbent material, adapted to be impregnated with oil or the like. The two pads 16 and 17, when the razor is inserted in the holder, as shown in Fig. 2, are suitably arranged and spaced apart, so as to engage the cutting edges B of the razor blade C and the pads 16 and 17 are preferably of such 45 thickness that when the razor guard A is forced into engagement with the flange 15 and the ledge 8, the pads will be slightly compressed, thereby forcing oil onto the edges of the razor blade C, as they contact 50 with and engage the pads. The oil pads 16 and 17 may be secured to the casing members in any suitable manner and in the present instance, the pad 17 is shown as 55 mounted upon a thin metal plate 18, (Fig. 6) which is provided with integral punched-out points or prongs 19, which are turned over into the body of the felt or pad, so as to 60 permanently secure it to the plate. The oil pad 17 is then secured in place against the 65 angular portion 13 in the hinged member

by turning over suitably projecting tongues 20 at each end of the pad, as more particularly shown in the section of Fig. 6. The pad 16 is likewise shown as provided with a similar backing plate 21, to which it is secured by similar prongs 19 and the pad 16 is secured to the bracket 1, by turned-in tongues 22 at each end of the pad, as more particularly shown in Figs. 1 and 5 of the drawings.

75 To facilitate ready insertion of the razor into the holder and oiler, and to prevent the cutting edge of the blade from striking the metal of the bracket, the pad 16 preferably extends forward and upward, beyond the hinge, as will be seen in Figs. 1, 2 and 4. The backing plate 21 is, in the present instance, preferably utilized as a limiting stop 80 to engage the under-side of the hinged member 11 for preventing it from dropping below the approximate level obtaining when the razor is supported in the device, after 85 the razor has been removed therefrom.

90 The operation of our improved oiling device and razor support will be readily understood from an examination of the drawings. To insert the razor, one edge of the guard A is inserted between the pad 17 and the flange 15 of the hinged member 11 and the latter is partially lifted, substantially as 95 shown in Fig. 1, after which the guard A is moved into a substantially horizontal position, being guided by the surface 9 so that the other edge B of the blade will be brought into contact with the oil pad 16, while the lower edge of the guard A slides over the ledge 8. As the razor is brought into this position, the hinged member 11 swings down to the position shown in Fig. 2 of the drawings and the razor becomes suspended from the ledge 8 and flange 15. The act of inserting the razor in the oiling device, as just 100 described, and drawing down the hinged member 11, forces the edges of the blade against the pads 16 and 17, thereby squeezing out a sufficient amount of oil to thoroughly lubricate the edges and protect them from rusting. The weight of the razor will keep the edges of the razor blade pressed 105 against the pads and the limiting stop 21 will prevent the hinged member from dropping too far down, either when the razor is in place in the device, or when removed; the latter condition being shown in Fig. 4 of 110 the drawings. Obviously, a spring, instead of gravity, could be used for controlling the movement of the hinged member with respect to the bracket member.

115 It may be desirable to provide our improved razor blade oiling device for use in the razor case, or for supporting the razor in the reversed position from that shown in Figs. 1 and 2 and previously described. Therefore, we have shown a modification in 120 Figs. 7 and 8. In this form, the oil pads 23

and 24 are mounted in a box-like casing 25, which is adapted to prevent loss or spreading of the oil. Preferably the longitudinal edges of the box 25 are provided with a plurality of spring fingers 26, which may be integral or otherwise, the upper ends of which are provided with suitable engaging noses or heads 27 to engage the respective edges of the razor guard A and thereby hold the edges B of the razor blade C in contact with the pads 23 and 24. The pressure of the spring clips 26-27 will be sufficient to keep the parts substantially in the position shown in Fig. 7 of the drawings, but will permit ready withdrawal of the razor from the box when it is desired to do so. This form of our oiling device, it will be understood, may be used in connection with the traveling set and carried in the ordinary razor case, or it may be used as a base for supporting the razor with the handle standing upright when the razor is inserted therein.

While we have shown our improved razor blade oiling device and support for the razor in the preferred forms it will be understood that we do not wish to be limited to the specific details of construction shown and described, for obviously, various modifications therein may be made, without departing from the spirit and scope of the invention. For instance, we do not wish to be limited to the particular construction of the hinged bracket and support, for the proportions and arrangement of the parts may be changed and parts may be left off or added, to form a device giving the same results and operating in a similar manner. Likewise, it may be desirable to change the form and shape of some parts and utilize other equivalent means for controlling the movement of the hinged parts. Furthermore, we believe that our improved automatic razor blade oiling device is particularly novel and the attached claims should be read accordingly.

45 We claim:—

1. In a safety razor blade oiler, the combination with a bracket adapted to be screwed to a support, a pad, adapted to be impregnated with oil, mounted on said bracket, a member hinged upon and supported by said bracket, a pad, adapted to be impregnated with oil, mounted upon said hinged member, and means carried by the bracket and said hinged member for engaging the razor blade guard for support-

ing the razor and holding the edges of blade in contact with said pads.

2. The safety razor blade oiler, as claimed in claim 1, in which means is carried by said bracket for limiting the movement of said hinged member and holding it in predetermined position when the razor is withdrawn therefrom.

3. In a safety razor blade oiler, the combination with a bracket, adapted to be attached to a wall or other support, said bracket being provided with an outwardly projecting ledge adapted for engaging the razor blade guard, an oil pad mounted on said bracket above said ledge, a hinged member pivoted to said bracket and provided at its outer edge with an inwardly turned flange corresponding to said ledge and an oil pad mounted on said hinged member above said flange, the arrangement and proportions being such that when the razor blade guard is engaged respectively by said flange and ledge, the edges of the blade will engage said oil pads and be held in engagement therewith by the weight of the razor.

4. The safety razor blade oiler as claimed in claim 3, in which said bracket and the hinged member are provided with means for securing the respective pads thereto.

5. A safety razor blade oiler, comprising a pair of oppositely disposed oil pads, mounted for movement toward and from each other, for oiling the edges of a double edge safety razor blade when assembled in the razor, and means associated with said pads for engaging the razor blade guard to thereby hold the edges of the razor blade in contact with the oil pads.

6. A safety razor blade oiler, comprising a pair of members resiliently movable toward and from each other and provided with oil pads mounted in position to engage the edges of the blade of an assembled safety razor when said members are moved toward each other and to release the same when they are moved away from each other.

7. The razor blade oiler, as claimed in claim 5, in which said members are adapted to engage the razor blade guard and means is provided for guiding the guard into position to be engaged and held by said members.

CHARLES F. STOKES.
JOHN F. STOKES.
